TAKE-UP MECHANISM FOR KNITTING MACHINES

Joseph A. Firsching, Utica, N. Y.

Application August 24, 1937, Serial No. 160,643

2 Claims. (Cl. 66—151)

My invention relates to a take-up mechanism for knitting machines and I declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to provide a take-up mechanism for knitting machines that will cause a tension on the knitted fabric as it rotates with the needles. Heretofore, there have been take-up mechanisms for knitting machines that would operate on a knitting machine where the needles and fabric made thereby were stationary and hence the take-up mechanism was built stationary on the machine, whereas in the present instance the take-up mechanism rotates with the needles and fabric.

The object will be understood by referring to the drawings in which:

Fig. 1 is an elevational view of a knitting machine showing the novel take-up device attached thereto.

Fig. 2 is a detail view showing a perspective of the take-up mechanism and the related parts of the knitting machine, parts of which are cut away, parts being in section.

Fig. 3 is a detail view enlarged, parts being broken away showing the beveled gears employed.

Fig. 4 is a detail view enlarged showing a central vertical section of beveled gear and immediate parts employed.

Fig. 5 is a detail enlarged view showing a perspective of a link and immediate members employed.

Referring more particularly to the drawings the parts of the knitting machine which are related to the take-up mechanism embody a frame 1 having legs 2. Frame 1 supports master shaft 3 on which is mounted to turn therewith master pulley 4. A bearing bracket 5 also aids in supporting shaft 3 and is formed integral or otherwise secured to one of the two upright plates 6, 6 which hold the upper annular ring plate above lower ring 8. A hand wheel 9 is fastened to turn with shaft 3, whereby to allow for turning said shaft 3 by hand if desired. A beveled gear 10 is keyed or otherwise fastened to turn with shaft 3 and meshes with the annular gear rack 11 formed integral with the rotary annular gear ring 12.

In order to balance hand wheel 9, a second hand wheel 15 is disposed diametrically opposite 55 and carried to turn with a short shaft 16 like-

wise mounted in bearings in the other upright 6. Similarly, a bevel gear wheel 17 is keyed or otherwise mounted to turn with shaft 16 and is in mesh with said annular gear rack 11.

Gear rack 11 is formed integral with rotary gear ring 12 as above stated. Said gear ring 12, however, is mounted to rotate in an annular bearing 18 made in annular rim 19. The inner part of gear ring 12 is shouldered at 20 to support needle plate 21 made in sections. Needle plates 21 are bolted at 22 to gear ring 12. Another plate 23 is mounted above gear ring 12, which is stationary, however, whereas gear ring 12 rotates therebeneath. Bolts 24 fasten plate 23 to rim 19 which is shouldered at 25 for the disposition of 15 the peripheral edge of plate 23.

An annular ring member 25 is bolted at 29 to plate 23 adjacent its inner peripheral edge. Furthermore, an annular L shaped member 26 is bolted at 27 to ring member 25. Both ring member 25 and L shaped member 26 are made in sections. There is an overhanging edge 28 formed on L shaped member 26. Beneath edge 28 and between the contiguous surfaces of member 26, ring 25 and needle plate 21 are disposed the upper and lower needle cams 30 and 31 respectively, which actuate the needles 32 in the process of knitting.

The yarn 33 is supplied from cones 34 disposed on an overhanging rack 35 to a combined sinker 300 and cast off wheel 36, more particularly described in a co-pending application filed July 13, 1937, Serial No. 153,385. Wheel 36 is mounted to rock with plate 37 which is pivotally supported to longitudinally movable member 38. Member 38 is rigidly fixed to shaft 39 having a spring pressed bearing in journal 40 formed integral or otherwise secured to shelf 41. Shelf 41 is made integral with annular L shaped member 26. A handle 42 is fixed to move shaft 41. There is also an adjusting screw 43 to hold handle 42 in a predetermined distance from journal 40 and a locking pin 44 to hold handle 42 when pulled out as more particularly described in the aforesaid application.

The novel take-up mechanism contemplates a take-up frame 50 which is pivotally supported on the under side of annular rotary ring plate 111. To this end a pair of bracket arms 52, 52 having their ends bent at right angles at 53, 53 are bolted at 54, 54 to the under surface of ring plate 111 and spaced apart. The lower ends of the bracket arms 52, 52 are equipped with bearing bushings 55, 55 for supporting a shaft 56. Shaft 56 extends beyond bracket arms 52, 52. Bearing bush-

ings 57, 57 of connecting bars 58, 58 are mounted on the extended parts of shaft 56, whereby to turn thereon. The opposite end of each of the bars 58, 58 is made with a bearing bushing 59 and clamp 61, whereby said bars 58, 58 are firmly held to shaft 60.

Moreover, the extreme ends of shaft 60 are held in the clamping parts 62, 62 of the side plates 63, 63 of frame 50. Plates 63, 63 are disposed in spaced parallel relation to each other and tied together at one end by shaft 65 which is carried in bearing bushings 66 formed integral with short shafts 67, 67 that in turn are made integral with plates 68. Plates 68 are bolted at 15 69, 69 to the ends of plates 63, 63.

The means for allowing the rocking of shaft 65 and, therefore, the take up frame 50 embodies a bell crank lever 70 which is fulcrumed on pivot 71 carried in bearings in depending hangers 72, 20 72 made integral with bracket 73. Crank lever 70 has one end connected by link 74 to shaft 65. Link 74 is bent at right angles at 75, projected through an aperture in the end crank lever 70 and tied with a cotter pin 76. The opposite 25 end of link 74 is threaded to bushing 77 having a sleeve part 78 through which shaft 65 is projected and held. An adjustable weight 80 has a sliding fit with the other end of lever 70. It is held in predetermined position by set screw 81. 30 An eye bolt 82 engages shaft 65. The free end 83 of eye bolt 82 is projected upwards through a loose aperture in horizontal extending finger 84 of bracket 73. A nut 85 is mounted to the upper free screw threaded end 83 of eye bolt 82 which 35 acts as an adjustment to limit the maximum downward rocking motion of take up frame 50 on shaft 56 as a fulcrum.

The means for engaging the knitted fabric 90, whereby to exert a pull or take up embodies 40 two fluted rollers 91, 92 which are disposed in parallel relation to each other and in contact, whereby the fabric 90 passing therebetween will be pulled downward as the rollers 91, 92 rotate in opposite directions. Said rollers 91, 92 are 45 mounted to turn on shafts 93, 94 which have bearings in side plates 63, 63 of frame 50.

The means for rotating fluted rollers 91, 92 in opposite directions contemplates spur gears 45 95, 96 which are in mesh with each other and mounted to turn with said shafts 93, 94 respectively. Said gears 95, 96 are disposed on the outside of side plate 63. Furthermore, a worm gear 97 is mounted to turn with said shaft 94 and disposed on the outside of the other plate 63. Worm 50 gear 97 is in mesh with a worm 98 having its trunnions or axle 99 mounted to rotate in bearings 100, 100 formed integral with upstanding part 101 of side plate 63.

Axle 99 is extended beyond adjacent bearing 60 100. A bevel gear 102 is fixed to turn therewith. Gear 102 is in mesh with a cooperating bevel gear 103 mounted to turn with shaft 104 which has a bearing in bushing 103' formed integral with side plate 63. A grooved pulley 105 is carried to turn on the opposite end of shaft 104. It is connected by a belt 106 with a power pulley 107. Pulley 107 is mounted to turn on a shaft 108 having a bearing in bushing 109 made integral with standard 110 that is bolted to the upper surface of annular ring plate 111. A bevel gear 112 is fixed to turn with shaft 108 and meshes with the annular gear rack 113 formed integral with stationary annular ring plate 55 51, whereby said bevel gear 112 will have a planetary

action as it rotates on its own axis and travels in a circle around gear rack 113.

The planetary motion of bevel gear 112 will cause pulley 107 to rotate as it travels around with bevel gear 112 and hence turn the gear 5 mechanism heretofore mentioned, to rotate take up cylinders or fluted rollers 91 and 92 when frame 50 is rocked downward to a given degree.

Annular ring plate 111 is mounted to slide on plate 51. The means for rotating said annular 10 ring plate 111 contemplates tying said plate 111 to rotating gear ring 12 thereabove. To this end upright posts 115, 115 disposed at diametrically opposite locations are, in each instance, slightly tapered at their upper ends and engage correspondingly formed apertures in gear ring 12 with a tight fit. The lower ends of each of said posts 115 project through an aperture in rotary plate 111, nuts 116, 116 are mounted to the threaded projecting ends to aid in holding plate 111 thereto. 15

The means for winding the knitted fabric 90 embodies a rectangular shaped member 120 fixed to turn with shaft 121 having bearings in depending brackets 122, 122 disposed diametrically opposite each other and bolted at 123, 123 to 20 the under side of annular rotating plate 111, whereby to rotate therewith.

The means for rotating member 120 axially contemplates a ratchet 125 mounted on shaft 121 and fixed to turn therewith. Ratchet 125 is engaged by a pawl 126 which is actuated intermittently by member 127. Member 127 is mounted on shaft 121 and rocked thereon by a pitman rod 128. Furthermore, member 127 has two arms 129 and 130 extending in opposite directions. 35 Pawl 126 is pivoted on pintle 131 supported in the free end of arm 129, whereas arm 130 has an elongated slot 132 for receiving adjustable bolt 133 which extends therethrough and into a threaded aperture made in link 134. A washer 40 135 is carried on said bolt 133. The lower end of pitman rod 128 is projected through and has a sliding fit in an aperture in the top horizontal part 136 of link 134. A nut 137 is screw threaded to pitman rod 128 below horizontal part 136 of member 134. A coiled spring 138 is disposed about pitman rod 128 and held under tension between the upper surface 136 of link 134 and adjustable collar 139 secured in place by a set screw 139', whereby to urge link 134 normally 45 downwardly.

Pitman rod 128 is bent at an angle at 140 to clear the inner edge of plate 111. A strap member 141 is threaded to the upper end of pitman 50 128 and engages crank shaft 142. Shaft 142 is carried in a loose bearing in bushing 143 formed integral with upstanding bracket 144 that is bolted at 145, 145 to rotating annular plate 111. A bevel gear 146 is mounted to turn with shaft 142 and meshes with the teeth of annular gear rack 60 113 which is mounted on the stationary annular ring plate 51 as above described.

Bevel gear 146 has a planetary motion around stationary gear rack 113 as it travels with rotating plate 111. Revolving on its own axis will cause a vertical reciprocating motion of pitman 65 128 which will in turn rock member 127 and hence cause pawl 126 to rotate intermittently or tooth by tooth ratchet wheel 125.

Ratchet wheel 125 is prevented from turning 70 in the opposite direction by pawl 150 pivoted on shaft 151 having a tight fit in a bearing made in the lower depending part 152 of member 122. The weight of free end 153 of pawl 150 holds the tooth 75 155 of pawl in engagement with ratchet 125.

When in operation, the knitted fabric 90 is lead down from needles 32 in tubular form within the enclosure formed by the needle holding member 21 and fed between fluted take up rollers 91 and 92 and on down to wind up member 120. Wind up roller 120 and take up mechanism comprising among other things rollers 91 and 92 will move around in a circle with needles 32. As the fabric 90 increases in length and being caught and held between fluted rollers 91 and 92 their weight and the weight of take up frame 50 and connected parts which is fulcrumed to rock on shaft 56 will exert a pull which is predetermined by the position of adjustable weight 80 on bell crank lever 70. The maximum rock motion however, will be governed by eye bolt 82. When said frame 50 has rocked down into dotted line position illustrated in Fig. 2, belt 106 connecting grooved pulleys 105 and 107 will be drawn sufficiently tight, whereby it will no longer slip over said pulleys 105 and 107 but on the other hand frictionally engage them to the degree that lower pulley 105 will turn with upper pulley 107. This will cause bevel gears 103, 102, worm 98, worm gear 97 and gears 96 and 95 to revolve, whereby take up rollers 91 and 92 will be revolved in opposite directions to feed fabric 90 therebelow onto rectangular rotating member 120. Rollers 91 and 92 will continue to turn until the surplus slack has been taken up or fed therebetween and below to member 120 when the tightness of knitted fabric 90 will again cause take up mechanism to be rocked back to initial or full line position illustrated in Fig. 2. In this latter position, belt 106 will slip again over the contiguous surfaces of pulleys 105 and 107, whereupon rollers 91 and 92 will become and remain idle until sufficient slack again occurs in knitted fabric 90 to allow frame 50 to rock down into dotted line position illustrated in Fig. 2 whereby to increase the tension on belt 106 to the actuating degree as above stated.

Although winding roll 120 has a continuous intermittent motion and take up rollers 91, 92 are stationary during certain periods, the take up rollers 91, 92 are moving downward with the rock fame 50 during this stationary period and will thereby feed the fabric downward during the stationary period of the rollers, whereby there is a continuous downward motion of the fabric which compensates for the stationary period of rollers 91, 92 to prevent excessive tension upon fabric 90 between winding roll 120 and take up rollers 91, 92. Furthermore, adjustable bolt 133 can be moved along arm 130 within the limits of slot 132 thereto to synchronize the turning of roll 120 with the feed of the fabric as it comes from between rollers 91, 92. Furthermore, spring 138 on pitman rod 128 will allow for a predetermined amount of yield to prevent excessive tension on fabric 90 between winding roll 120 and take up rollers 91, 92.

Simultaneously with this periodic rotation of rollers 91 and 92 to take up the slack in knitted

fabric 90, rectangular shaped member 120 will be rotated intermittently by pawl 126 which is rocked back and forth by member 127. Member 127 in turn is rocked alternately in clockwise and counterclockwise direction by the vertically reciprocating pitman rod 128 which is connected to the eccentric shaft 142. Shaft 142 is rotated by bevel gear 146 which is turned axially as said gear 146 moves around on annular gear rack 113.

Moreover, simultaneously with the above mentioned rocking motion of take up mechanism frame 50 and the intermittent rotation of wind up member 120, both these aforementioned parts will revolve with needles 32 and fabric 90 because of the engagement of plate 111 with the revolving gear ring 12, whereas gear ring 12 is made to revolve through master pulley 4 bevel gear 10 and gear rack 11 as above stated.

Having thus described my invention what I claim as new and desire to secure by Letters Patent is as follows:

1. In a take up mechanism for knitting machines, a rotary gear ring for carrying needles for knitting a fabric, another ring connected to said first named gear ring, a rock frame connected with said second named ring, rollers supported in said rock frame for engaging the knitted fabric, a lever mounted in said knitting machine, a link connecting said lever with said rock frame, a weight mounted on said lever for governing the amount of tension of said rock frame on said fabric, and gear means connected with said knitting machine, whereby to rotate said take up rollers, a rectangular member for winding said knitted fabric after passing below said take up rollers, a gear mounted on said second named ring, a crank shaft mounted to turn with said last named gear, a ratchet wheel mounted to turn with said rectangular shaped member, a pawl engaging said ratchet wheel, a rock member carrying said pawl and a rod connecting said last named rock member with said crank shaft, whereby to rotate said rectangular shaped member intermittently.

2. In a take up mechanism for knitting machines, a rotary gear ring for carrying needles, whereby to knit a fabric, a ring plate connected to turn with said rotary gear ring by posts, a rock frame connected with said ring plate by means of rock bars, rollers carried in said rock frame for engaging the knitted fabric, means for controlling the rocking of said frame, gears connected with said rollers, a pulley connected with said gears, another pulley mounted on said rotary ring plate, a gear connected to turn with said last named pulley and mounted on said rotary ring plate, a stationary gear ring meshing with said last named gear, whereby to turn said gear and pulley, a belt connecting said pulleys, a roll for winding the fabric thereon and means connected with said last named gear ring for actuating said wind up roll intermittently.

JOSEPH A. FIRSCHING.
